UNITED STATES PATENT OFFICE.

GEORGE J. RYMAL, OF DENVER, COLORADO.

COMBINED HOT-WATER HEATER AND KITCHEN-RANGE.

1,128,053.

Specification of Letters Patent.

Patented Feb. 9, 1915.

Application filed March 14, 1914. Serial No. 824,672.

To all whom it may concern:

Be it known that I, GEORGE J. RYMAL, a citizen of the United States, residing in the city and county of Denver and State of Colorado, have invented certain new and useful Improvements in Combined Hot-Water Heaters and Kitchen-Ranges; and I do declare the following to be a full, clear, and exact description of the invention, such as will enable others skilled in the art to which it appertains to make and use the same, reference being had to the accompanying drawings and to the letters and figures of reference marked thereon, which form a part of this specification.

My invention relates to improvements in combined hot water heaters and kitchen ranges, my object being to provide a construction in which the waste heat from the hot water heater or boiler is utilized to heat the range element or member of the structure, the range portion being located above the boiler portion. In my improved construction, the top of the range containing the holes and covers is directly above the fire box of the heater and the flane therefrom comes directly in contact therewith, thus giving all the advantages that can be enjoyed from a kitchen range having its own fire box which performs the one function only. Furthermore, flues leading from the fire box in the rear of the lid portion of the range, communicate with a hot air jacket surrounding an oven which is located above and projects forward over the lid portion of the range. As the flame and products of combustion enter this hot air chamber and circulate around the same before passing to the smoke flue, this oven may be utilized for baking and for all other purposes to which the ordinary range oven is applicable, and the heat which supplies it would otherwise be wasted through the smoke flue, in the absence of the oven. It is evident that in my improved construction, the heat from the boiler portion of the apparatus performs a double function of heating the water for a hot water system and supplying the kitchen range.

It should be explained that my improvement is intended for use in comparatively small dwelling houses located either in the city or country and it is capable of supplying such houses with a hot water system adapted for heating three or four rooms, and at the same time, furnish a kitchen range. In this manner, there is a comparatively

large saving in fuel and the entire structure is not unduly large for placing in a kitchen of the usual size.

Having briefly outlined my improved construction, I will proceed to describe the same in detail, reference being made to the accompanying drawing, in which is illustrated an embodiment thereof.

In this drawing, Figure 1 is a front view of my improved hot water heater and range. Fig. 2 is a rear view of the same, partly in vertical section taken on the line 2—2, Fig. 3, looking toward the left. Fig. 3 is a central vertical section taken on the line 3—3, Fig. 2, looking toward the right. Fig. 4 is a horizontal section taken through the fire box of the structure on the line 4—4, Fig. 3, viewed in the direction of the arrow.

The same reference characters indicate the same parts in all the views.

Let the numeral 5 designate the boiler portion of the structure which consists of a fire box 6, surrounded by a jacket or hot water chamber 7, from whose upper portion leads a hot water pipe 8 to a hot water radiator 9. It is evident that this pipe 8 may be connected with the desired number of hot water radiators and that the return pipe 10 may lead from the last radiator of the system, the radiators being connected in series, so to speak, with the circulatory system. The pipe 10 communicates as shown at 12, with the lower part of the hot water chamber or jacket 7. The water, when it returns to the lower part of the jacket is, of course, cooled and subsequently reheated in the jacket, and in this way the circulation is established the same as in ordinary hot water boilers employed for house heating purposes.

Within the central part of the boiler is arranged the fire box 6 in which is also located a pipe coil 13, from the upper extremity of which leads a hot water pipe 15, which communicates at 16 with the top of a boiler 17, from which leads a service pipe 18. From the bottom of the boiler 17 leads a pipe 18, which communicates with the lowermost convolution of the pipe coil within the fire box. By virtue of this construction it will be understood that my improvement not only supplies water for heating the rooms of the house, but also furnishes the necessary hot water for the usual range boiler from which hot water is taken for kitchen and other uses.

Arranged directly above the fire box 6 is

the top 20 of the range feature of my improved construction, while below the fire box is an ash pit 21 provided with a front door 22. The fire box has a bottom grate 23 to 5 which is secured a bar 24 adapted for use for shaking purposes.

The top 20 of the range is provided with a number of openings which are normally closed by the usual covers or lids 25. The 10 front of the structure between the top 20 and the front wall 26 is provided with a hinged door 27 which is adapted to be opened for supplying fuel to the fire box.

In the rear of the top 20 is located a number of openings 28, one being centrally located and surrounded by the lower extremity of a pipe 36, passing up through registering openings 29, 30 and 31, formed in the rear part of the oven 32, whose chamber 33 is surrounded by a jacket 34. The opening 29 is in the bottom 35 of this jacket while the openings 30 and 31 are in the top and bottom portions of the oven 33 proper. The pipe or flue 36 is in alinement or registers at its upper extremity with a smoke flue 37 which enters the opening 38 in the top of the jacket 34. The upper extremity of the pipe 36 and the lower extremity of the smoke flue are separated, as shown at 39, whereby the products of combustion are allowed to enter the jacket before passing into the flue. The other openings 28 in the top 20 of the range portion of the structure are arranged on opposite sides of the center 35 opening and each is surrounded by the lower extremity of a short pipe or flue 40, which passes through an opening 41 formed in the bottom of the jacket and communicates with the jacket below the bottom of the oven 33. 40 The products of combustion from the fire box passing through the pipes 40, thus enter the lower part of the jacket 34 and circulate around the oven member 33 before entering the smoke flue. By virtue of this arrangement the products of combustion are practically deprived of their heat units before entering the smoke flue with the result that 45 there is comparatively little loss of heat.

Each of the pipes 36 and 40 is provided 50 with a damper or cut off 42. When it is desired to prevent the direct exit of a portion of the products of combustion, through the pipe 28 and into the smoke flue, the damper of the pipe 36 may be closed (see 55 Figs. 1, 2 and 3), thus compelling all of the products of combustion to pass through the flues 40 into the hot air jacket 34, whereby the heat from the fire box is utilized to the best possible advantage for heating the 60 oven. It is evident that by means of the dampers in the pipes 36 and 40, the supply of heat to the oven may be regulated at will.

Should it be desired to reduce the temperature of the oven, the two dampers of the pipes 40 may be closed and the damper 42 left open, thus compelling all of the products of combustion to pass through pipe 36, which is in direct alinement with the smoke flue, as heretofore explained. The oven 32 has doors 43 of the usual or any ordinary construction, closing openings communicating with the chamber 33.

From the foregoing description, the use of my improved construction will be readily understood and need not be further explained in detail.

Having thus described my invention, what I claim is:—

1. The combination of a fire box, a boiler surrounding the same, a radiator system in communication with the boiler, the fire box being enlarged above the boiler, a range top located directly above and covering the entire fire box, an oven located at said top and provided with a surrounding jacket, three flues leading from the fire box to said jacket, one of said flues being centrally located and passing through the lower part of the oven jacket, the oven proper and communicating with the upper part of the jacket, while the other flues are arranged on each side of the central flue and communicate with the bottom portion of the oven jacket, and a smoke flue communicating with the jacket directly above the central flue, leading from the fire 95 box.

2. The combination of a fire box, a boiler surrounding the same, a radiator system in communication with the boiler, the fire box being enlarged above the boiler, a range top located directly above and covering the entire fire box, an oven located above said top and provided with a surrounding jacket, three flues leading from the fire box to said jacket, one of said flues being centrally located and passing through the lower part of the oven jacket, the oven proper and communicating with the upper part of the jacket, while the other flues are arranged on each side of the central flue and communicate with the bottom portion of the oven jacket, means located in the two side flues whereby the products of combustion may be directed entirely through the central flue, and a smoke flue communicating with the 105 jacket, directly above said central flue, for the purpose set forth.

In testimony whereof I affix my signature in presence of two witnesses.

GEORGE J. RYMAL.
